BRACELET LINK

Theodore E. Cayer, Taunton, Mass.

Application September 15, 1953, Serial No. 26,811

Term of patent 3½ years

(Cl. D45—4)

To all whom it may concern:

Be it known that I, Theodore E. Cayer, a citizen of the United States of America, residing in Taunton, county of Bristol, State of Massachusetts, have invented a new, original, and ornamental Design for a Bracelet Link, of which the following is a specification, reference being had to the accompanying drawing forming a part thereof.

Fig. 1 is a top plan view of a bracelet link, showing my new design;

Fig. 2 is a side elevational view thereof; and Fig. 3 is an end elevational view thereof.

I claim:

The ornamental design for a bracelet link, substantially as shown.

THEODORE E. CAYER.
